UNITED STATES PATENT OFFICE

2,503,876

WIREWAY OR LIGHT STRIP ASSEMBLY

Carl Krauss, Chicago, Ill.

Application February 9, 1946, Serial No. 646,619

8 Claims. (Cl. 138—75)

1

The present invention relates to a wire-way or light strip assembly and especially to a novel removable closure, as well as a novel mounting for lamp holders or sockets for fluorescent lighting.

Among the objects of the present invention is to provide a novel end plate or closure mounting for a wire-way or light strip assembly comprising a channel-shaped base or strip adapted to be mounted upon the ceiling, side wall or other support wherever it is desired to mount a fluorescent lighting unit, a cover therefor and the present novel end or intermediate plates for supporting the lamp holders or sockets and provided with a novel attaching means whereby these plates may be quickly and easily applied and locked in their proper position, or may be readily removed or disassembled when required.

A further object of the present invention is the provision of a novel removable closure for wire-ways and various forms of channel members, including raceways for carrying wires, cables or the like.

The invention further comprehends a novel means and manner of quickly mounting and securely retaining a cover plate upon a channel, raceway or the like.

Further objects are to provide a construction of maximum simplicity, efficiency, economy and ease of assembly and operation, and such further objects, advantages and capabilities as will later more fully appear and are inherently possessed thereby.

The invention further resides in the construction, combination and arrangement of parts illustrated in the accompanying drawings, and while there is shown therein a preferred embodiment, it is to be understood that the same is susceptible of modification and change, and comprehends other details, arrangements of parts, features and constructions without departing from the spirit of the invention.

In the drawings:

Figure 1 is a fragmentary view in perspective of a continuous channel or wire-way forming the base of a light strip assembly.

Fig. 2 is a fragmentary view in perspective of the assembly ready for reception of the fluorescent lamps or luminous tubes.

Fig. 3 is a view in perspective of a lamp holder plate of the type shown in Fig. 2, and which is employed where a series of fluorescent lamps are mounted.

Fig. 4 is a fragmentary view in perspective of a snap-on cover as shown in Fig. 2.

Fig. 5 is a perspective view of a lock-on plate 55

2

of the type shown in Fig. 2, which is adapted to be mounted upon the channel at one end of the installation.

Fig. 6 is a broken view in side elevation of an installation similar to Fig. 2 but showing a continuous channel and assembly, the lamps and lamp holders or sockets being shown in dotted outline.

Fig. 7 is a bottom plan view of the wire-way or light strip assembly of Fig. 6.

Fig. 8 is a disassembled view of the closure plates shown in Fig. 7 for enclosing the continuous channel.

Fig. 9 is a fragmentary enlarged bottom plan view of one of the cover plates, with the heads of the attaching screws removed to show more clearly the manner of assembly of the closure plate upon the channel, the view being taken in a plane represented by the line 9—9 of Fig. 10.

Fig. 10 is a view in vertical cross-section through the channel and closure plate and taken on the line 10—10 of Fig. 9.

Fig. 11 is an enlarged view in vertical cross-section taken in a plane represented by the line 11—11 of Fig. 7.

Fig. 12 is an enlarged view in vertical cross-section taken in a plane represented by the line 12—12 of Fig. 7.

Fig. 13 is a fragmentary perspective view of a surface raceway employing the novel lock-on or closure plate.

Referring more particularly to the disclosure in the drawings and the novel embodiment therein selected to illustrate the invention, the present invention is shown more particularly in connection with a wire-way or light strip assembly consisting of a channel member 1, providing a base for one or more fluorescent lamps or luminous tubes 24 and adapted to be mounted in any suitable manner upon the ceiling, side wall or other support. The ends 2 of the opposite sides of the channel are each crimped to form a bead 3 and provided with an inturned flange 4. The crimped portion or bead 3 provides a convenient method for applying a snap-on cover 5, also of channel shape, with its opposite sides or flanges 6 crimped in such manner as to snap on to the crimped portion or bead 3 of the channel and thereby provide a convenient method of assembly of the closure upon the channel.

In the prior types of light strip assemblies, the attachable cover is made of a predetermined length and provided at its ends with cut-outs or recesses for mounting the lamp holders or sockets 10. Thus, the cover would necessarily

have to support these lamp holders or sockets, the fluorescent or luminescent lamps supported by the latter, the transformer, ballast, etc. Due to the weight of these latter elements, the snap-on cover is not satisfactory unless some means is provided to prevent accidental disengagement of the cover from the channel or light strip.

Another distinct disadvantage to such prior constructions is that the ballast or choke coil is supported on this cover along with the lamp holders or sockets, and when the cover is removed these parts and the associated wiring will loosely depend from the end connections. Thus when access is required for repair or replacement of any of the enclosed parts, such parts hang loose and are in the way of the electrician or repair man. Furthermore, their replacement when the cover is again attached entails additional difficulties in order to align the wires properly and prevent them from becoming damaged or pinched between the channel and cover.

The present invention eliminates the above objections and disadvantages in that the cover does not carry the lamp holders or sockets and the lamps or tubes supported thereby, but these are supported upon end or intermediate plates provided with novel locking means for locking onto the continuous channel or light strip.

As shown, an intermediate plate 6^a is provided with crimped flanges 7, 7 at its opposite sides, a tongue or ear 8 at each end thereof, a cut-out 9 adapted to receive and permit projecting therethrough of a pair of lamp holders or sockets 10 shown in back-to-back abutting relation, an opening 11 for a starter 12 and a pair of substantially L-shaped slots 13 projecting in opposite directions and each desired to receive an attaching screw or bolt 14 having its shank 15 projecting through the slots 13 and its end adapted to receive a nut 16 disposed at the interior of the plate.

As shown more clearly in Figs. 9 and 10, these nuts are preferably of square or polygonal form, and the slots are so disposed and arranged that when the operator mounts the plate 6^a upon the channel or light strip 1 and turns the screw 14 to retract the nut 16, the turning of the screw in a clockwise direction automatically causes the screw and nut to move outwardly in the slot 13 and into the outer end 16^a thereof.

As shown, one of the screws has been tightened and when so tightened, the nut traveling with the screw in the slot projects over and engages the inner side of the turned flange 4 on the channel or light strip 1, and tightly embraces the thickness of the plate 6^a and flange 4 between the head of the screw or bolt and the nut. It is further to be noted that in this position the nut, if it has any tendency to turn, will abut against the adjacent side wall of the channel 1 and will thus be locked against turning movement.

When the screw or bolt is loosened as shown at the right-hand side of Figs. 9 and 10, it will move into the position therein shown with the shank of the screw or bolt received in the inner end of the slot 13, and in which position the nut is spaced inwardly from the flange 4 to permit the plate to be readily removed and/or replaced.

In Fig. 5 there is disclosed another form of plate 17 adapted to be disposed at one end of the channel or light strip, and provided with the oppositely extending slots 13, a tongue or lip 8 at one end only and a notch or cut-out 18 at the opposite end for receiving a single lamp holder

or socket 10. In this form of the invention the slots function in the same manner as in Fig. 3, and the tongue or lip 8 is inwardly offset or bent in such manner as to overlie the end 19 of the cover 5 for the continuous channel or light strip, and each is provided with aligned openings 20 for receiving a locking screw or bolt 21. In the form shown in Fig. 3, the tongues, lips or projections 8 are also provided with openings 20 adapted to be aligned with similar openings 20 in the adjacent ends of the cover 5 for locking these parts together. It is to be noted that the cover plates or closures 5 bear no weight of the lamp assembly and, therefore, are securely retained by the snap-on feature, augmented by the screws 21 passing through the aligned opening 20 in the adjacent portions of the cover plates 5 and plates 6^a and 17.

In Figs. 6, 7 and 8, another form of plate 22 is provided or added to the assembly. This plate is similar to the plate 17, except that it is shown provided with a cut-out 23 through which may project a starter 12 for the lamp assembly.

Where the cover plates 5 are of any considerable length, the invention comprehends that the snap-on feature alone need not be relied upon for supporting the cover. In fact, when such cover plates are of any substantial length, the snap-on feature may be eliminated. In either event, two or more of the slots 13 may be provided and a locking or latching means similar to that provided on the plates 6^a, 17 and 22 may be employed for positively locking these plates onto the channel.

Each lamp holder or socket is shown as adapted to receive the opposite ends of a fluorescent lamp or luminous tube shown in dotted outline at 24 in Fig. 6. These luminous tubes may be of any desired length and may be provided in series longitudinally or in parallel relation as is now the common practice. In the channel or light strip 1 is provided the usual ballast 25 shown in dotted outline in Fig. 10, the necessary starter 12 having an end projecting through an opening 11 or 23 as shown in Figs. 2, 3, 7 and 8, and the ballast clamping brackets 26 shown in Fig. 10. These clamping brackets are provided with angularly disposed legs or projections 27 and 28, each adapted to rest upon a flange 4 at the opposite sides of the channel or wire strip and with the base 29 of the bracket provided with a clamping screw 30 adapted to seat against a flange 31 projecting from the base of the ballast 25.

The novel mounting plates although specifically referred to in connection with a wire-way or light strip assembly for fluorescent lamps, are also admirably adapted for use in a surface raceway 32 of the type shown in Fig. 13, which may be assembled along a ceiling wall or other support for carrying the wires or cables for supplying current for operating various machinery or power supply as required. Such prior surface raceways are frequently provided with an elongated cover which must be removed whenever it is desired to splice lead lines onto the cables in the raceways. By the present invention, it is a simple matter to provide at any suitable intervals along the channel 33 a cover 34 formed of sections of any suitable lengths and between such sections intermediate closure plates 35 suitably spaced apart and which may be readily removed but provided with the novel mounting arrangement shown in connection with the plates 6^a, 17 and 22. This comprises inwardly extending flanges 36 on the opposite sides of the channel or base

33, slots 13, attaching screws or bolts 14 and nuts 16 for anchoring the closure plates onto the flanges 36. An inwardly bent tongue or lip 37 having a width approximately that of the opening between the edges of the flanges 36 is provided at each end of the closure plates 35 and each tongue or lip is provided with an opening 38 adapted to align with an opening 39 in the adjacent cover 34 for the reception of screws or other attaching or securing means. The tongues or lips 37 are disposed adjacent the edges of the flanges 36 and maintain the latter in spaced relation.

In addition, these plates may be provided with suitable knockouts 40 for facilitating the running of lead lines to the cables 41 enclosed in the channel. Thus, in this construction all that is necessary to secure access to the cables is to remove an adjacent cover 34 by removing the screws in the openings 38 and 39, loosen the screws or bolts 16, and then remove the lock-on plate 35 which at its opposite ends is connected to the covers. Leads then may be spliced to the cables and extend through the opening provided by the knockout 40, after which the cover and closure plates are again assembled and secured in position. Expansion bolts or the like 42 may be employed for hanging or securing the wire-way or surface raceway in position. If desired, the cover plates 34 may also be retained by the present novel attaching means, especially if they are of any considerable length.

The projecting ears or tongues in the various forms of the invention have the added feature of grounding the adjacent parts.

Having thus disclosed my invention, I claim:

1. In a light fixture including a lamp holder, a channel-shaped light strip provided with an in-turned flange at the opposite sides, a mounting plate for supporting the lamp holder on the light strip, and means for detachably locking the plate upon the in-turned flanges of the light strip comprising oppositely disposed and substantially L-shaped slots in the mounting plate adjacent the opposite edges of the plate with a slot positioned adjacent each flange on the light strip, a screw loosely carried in each slot, and a nut carried on each screw at the interior of the plate and adapted to engage an adjacent flange to lock the plate thereon, said slots permitting free movement of the screws and the slots, screws and flanges being so constructed and arranged as to permit the ready removal of the plate when the screws are loosened and moved to one end of the slots away from the flanges, and to cause locking of the plate upon the flanges when the screws are tightened and moved to the other end of the slots.

2. A novel channel and closure assembly, comprising a channel member provided at its opposite sides with an in-turned flange, a cover plate therefor adapted to form a closure for the channel, and means for detachably locking the cover plate upon the channel and including a pair of elongated and angularly arranged slots provided in the plate with the outer end of each slot offset with respect to the inner end and with such outer end disposed adjacent the flanges, a screw received in each slot and a nut mounted on the screw on the interior of the plate, said slots being so contoured that as the screws are tightened, such rotation causes the screws to follow the contour of the slots and move outwardly whereby the nuts move over and engage and seat against the flanges to thereby lock the plate in position.

3. A novel channel and closure assembly, com-

prising a channel member provided at its opposite sides with an in-turned flange, a cover plate therefor adapted to form a closure for the channel, and means for detachably locking the cover

5 plate upon the channel and including a pair of oppositely extending and substantially L-shaped slots provided in the opposite sides of the plate and adjacent the flanges, and a binding screw laterally movable in each slot and provided with 10 a nut on the inner end of the screw for interlocking engagement with a flange when the screw is tightened and moved toward the outer end of its slot.

4. A novel channel and closure assembly, comprising a channel member provided at its opposite sides with an inwardly projecting flange, a cover plate forming a closure for the channel, and interlocking means for detachably securing the plate on the channel and including a substantially L-shaped slot adjacent the opposite edges of the plate with these slots disposed in opposite relation, and a binding screw loose and movable in each slot and provided with a nut on the inner end of each screw for interlocking engagement with a flange when the screw is tightened and moved toward the outer end of its slot.

5. A novel channel and closure assembly, comprising a channel member provided at its opposite sides with an inwardly projecting flange, a cover plate forming a closure for the channel, and interlocking means for detachably securing the plate on the channel and including a substantially L-shaped slot adjacent each edge of the plate with these slots disposed in opposite relation and each contiguous to a flange on the channel member, and adjustable means carried and freely movable in each slot for interlocking engagement with an adjacent flange.

6. In a light strip assembly, a channel-shaped 40 light strip provided with an external bead and an inwardly projecting flange at its opposite sides, a cover for enclosing the channel through the greater portion of its length, a mounting plate at the opposite ends of the cover for receiving and 45 supporting holders for the opposite ends of a luminous tube, means for connecting an end of the plate to the cover, and means for detachably securing the mounting plates upon the light strip and including an upstanding flange at each side 50 of the mounting plate having a complementary bead for receiving the beads on the light strip and interlocking means for detachably locking the plates to the projecting flanges, said interlocking means including an elongated and substantially 55 arcuate slot provided in the plates adjacent the opposite edges thereof and with the outer end of these slots disposed adjacent the flanges on the light strip, a binding screw projecting upwardly through and freely movable 60 along each slot and a nut on the inner end of each screw for interlocking engagement with a flange on the light strip when the screw is tightened and moved toward the outer end of its slot.

7. In a light strip assembly, a channel-shaped 65 light strip provided with an inwardly projecting flange adjacent its opposite ends, a cover for enclosing the channel through the greater portion of its length, a mounting plate at the opposite ends of the cover for receiving and supporting a lamp 70 holder for receiving an end of a fluorescent tube, means for securing an end of the mounting plate to an adjacent end of the cover, and means for detachably securing the mounting plates upon the flanges of the light strip including a substantially L-shaped slot in the plates adjacent

75

7
each of the opposite edges of the mounting plates and with the outer end of these slots disposed adjacent a flange of the light strip, and an interlocking screw and nut carried and freely movable in each slot for interlocking engagement with a flange on the light strip when the screw is tightened and moved toward the outer end of its slot.

8. In a light strip assembly, a channel-shaped light strip provided with an inwardly projecting flange at its opposite sides, a cover for enclosing the channel through the greater portion of its length, a mounting plate adjoining the cover for receiving and supporting holders for the opposite ends of a luminous tube, means for joining the mounting plate to the cover, and means for detachably securing the mounting plate upon the light strip and including an upstanding flange projecting over the opposite sides of the light strip, and means for detachably locking the 10 mounting plate on the inwardly projecting

flanges of the light strip, including an elongated slot adjacent the opposite edges of the plate with the outer end of each slot offset with respect to the inner end and with such outer end positioned adjacent a flange of the light strip, and a screw and nut carried and freely movable in each slot for interlocking engagement with a flange on the light strip when the screw is tightened and moved toward the outer end of its slot.

CARL KRAUSS.
